Patented Dec. 31, 1963

197,242

GRASS CATCHER

Harold W. Pirie, St. Louis, Mo., assignor to The Perfection Manufacturing Company, St. Louis, Mo., a corporation of Missouri

Filed Apr. 15, 1963, Ser. No. 74,451

Term of patent 14 years

(Cl. D40—1)

FIG. 1

FIG. 2

FIG. 3

FIG. 4

FIG. 5

FIG. 6

FIG. 1 is a top plan view of my new design of a grass catcher;

FIG. 2 is a front perspective view thereof;

FIG. 3 is a bottom plan view thereof;

FIG. 4 is an end elevational view as seen from the left of FIG. 2;

FIG. 5 is a rear elevational view thereof, and

FIG. 6 is an end elevational view as seen from the right of FIG. 2.

I claim:

The ornamental design for a grass catcher, substantially as shown.
